UNITED STATES PATENT OFFICE.

JOHN M. C. JONES, OF GIBSON CITY, ILLINOIS.

CORN AND SYRUP FEEDER FOR CANNING FACTORIES.

SPECIFICATION forming part of Letters Patent No. 748,744, dated January 5, 1904.

Application filed October 1, 1903. Serial No. 175,382. (No model.)

To all whom it may concern:

Be it known that I, JOHN M. C. JONES, a citizen of the United States, residing at Gibson City, in the county of Ford and State of Illinois, have invented certain new and useful Improvements in Corn and Syrup Feeders for Canning Factories; and I do declare the following to be a full, clear, and exact description of the invention, such as will enable others skilled in the art to which it appertains to make and use the same.

This invention relates to improvements in feeding-machines for canning factories.

The object of the invention is to provide a machine of this character by which corn and syrup may be mixed and fed to the cooker in proper proportioned and predetermined quantities.

A further object is to provide such a machine which will be strong, durable, and comparatively simple in construction, reliable and efficient in operation, and well adapted to the purpose for which it is designed.

With these and other objects in view the invention consists of certain novel features of construction, combination, and arrangement of parts, as will be more fully described, and particularly pointed out in the appended claims.

30 In the accompanying drawings, Figure 1 is a rear perspective view of the feeder. Fig. 2 is a front elevation of the same. Fig. 3 is a side elevation, partly in section. Fig. 4 is a detail horizontal sectional view of the steam-valve casing and valve. Fig. 5 is a detail perspective view of the steam-valve operating arm or lever.

Referring to the drawings more particularly, 1 denotes an upright frame of suitable construction supporting at its upper end a hopper 2, feed-cylinder 3, and chute 4. Within the hopper and feed-cylinder is adapted to reciprocate a piston 5, fixed to the upper end of a vertically - reciprocating piston - rod 6, which works through the bottom of the chute 4 and through a stuffing-box 7, fixed to said bottom. The lower end of the piston-rod 6 is connected to a vertically - reciprocating cross-head 8, which slides on and is guided by vertically-disposed bars 9, fixed to the main frame.

10 denotes a pitman-rod, the upper end of which is pivotally connected to the cross-head and the lower end of which has a sliding connection with the slotted end of a crank-arm 11, fixed to a shaft 12, which is journaled in suitable bearings in the lower end of the frame 1, whereby when said shaft is turned the crank thereon will reciprocate the piston-rod 6 and piston 5 through the medium of the pitman-rod 10.

On one end of the shaft 12 is fixed a spur gear-wheel 13, which is adapted to mesh with a similar gear 14, fixed on a counter-shaft 15, also journaled in suitable bearings in the lower end of the frame 1. On the outer end of the shaft 15 is mounted a band wheel or pulley 16, by which said shaft is driven.

On the upper side of the chute 4, near the mouth of the same, is arranged a valve-chamber 17, in which a cut-off valve 18 is mounted to reciprocate, said valve being adapted to slide into and out of said chamber to open and close the discharge end of the chute 4. The valve 18 is provided with an upwardly-projecting stem 19, which passes through the top of the chamber 17 and has its upper end guided in a bracket 20. To the stem 19 is adjustably secured the upper end of a valve-shifting rod 21, the lower end of which is secured to the outer end of an arm 22, the opposite end of said arm being pivotally connected to the frame 1 of the machine, as shown at 23.

24 denotes a block adjustably secured to the arm 22 and adapted to be engaged by a cam 25, fixed on the shaft 12. As the cam is brought into engagement with the block 24 it rocks the arm 22, raises the valve-rod 21, and opens the valve 18. By adjusting the block 24 along the arm the time of closing the valve may be regulated, said valve closing by gravity as soon as the cam 25 moves from beneath the block 24 on the arm 22, as will be understood.

26 denotes a steam-valve casing having an inlet-port 27 and an outlet-port 28. Within the casing is mounted an oscillating valve 29, which is provided with a stem 30, to which is fixed a crank-arm 31. Said valve is adapted to be oscillated to cover and uncover said outlet-port to intermittently discharge steam from said valve-casing.

32 denotes a steam-supply pipe which communicates with the steam-inlet port 27, and 33 denotes a discharge-pipe which communicates with the outlet-port 28 and is adapted to conduct steam from the valve-casing 26 and discharge the same into the cylinder 3 below the piston 5.

The operation of the valve 29 is effected by means of a vertically-disposed rocking arm 10 or lever 34, which is pivotally connected at about its center to the frame 1 and is formed at its lower end with an offset 35. The arm or lever 34 is provided on its inner side and throughout its length with a channel or groove 36, in which is adapted to work a pin or lug 37, which projects from the side of the cross-head 8, and as said cross-head lowers said pin moves down in the groove in the arm or lever 34, and when it reaches the offset 35 at the 20 lower end thereof said lever will be rocked. The upper end of the lever is connected to the crank-arm 31 of the valve 29 by means of a link 38, and as said lever or arm is rocked the same will shift said valve to open and close 25 the outlet-port, as hereinbefore described.

The purpose of introducing steam into the cylinder 3 is to break the vacuum beneath the piston as the same is rising on its up-stroke, thus causing the piston to be much 30 more easily moved. As soon as the piston moves up far enough to admit the corn the steam will condense by contact with the cold corn. This condensation will then cause a 35 vacuum to be formed beneath the piston as it lowers on its downstroke, thereby facilitating the lowering of the same, the parts being so arranged and timed that the admission of steam will be made at the proper moment.

40 39 denotes a syrup-pump supported upon a portion of frame 1, and 40 denotes the piston or plunger adapted to reciprocate in said pump.

41 denotes the piston or plunger rod, pivotally connected at its upper end to one end of an arm 42, the opposite end of which is pivotally connected to the frame 1, as at 43. The arm 42 and piston 40 are actuated by means of a pitman rod or link 44, which is 50 connected at one end to the arm 42 near the center of the same, the opposite end of the pitman rod or link 44 having an adjustable connection with a crank-arm 45, fixed to the shaft 15. By adjusting the connection of the 55 rod or link 44 with the crank-arm 45 the length of the stroke of the pump-piston may be varied, thereby causing the pump to supply more or less syrup, as desired.

46 denotes the syrup-supply pipe, which 60 communicates with the lower end of the pump 39 and has arranged therein a check-valve 47, which is adapted to open on the upward stroke of the pump-piston to admit syrup to the pump.

65 48 denotes a syrup-discharge pipe connected at its lower end to the supply-pipe and

having its upper end opening into the valve-chamber 17, whereby the syrup is forced by said pump into said chamber in predetermined quantities, such discharge being regulated by means of the adjustable connection of the pitman rod or link 44 with the crank-arm 45, which will regulate the length of the stroke of the pump-piston, thereby causing more or less syrup to be drawn into and discharged from the pump at each stroke of the piston. A check-valve 49 is arranged in the discharge-pipe 48 adjacent to the connection of the same with the supply-pipe and is adapted to open on the downstroke of the 70 pump-piston to permit the syrup drawn into the pump to be forced through the discharge-pipe, said valve closing as soon as the pump-piston begins its upstroke. The operation of the pump-piston is so timed that the syrup will 75 be discharged into the valve-chamber, from whence it runs into the discharge-chute just as the corn is being discharged through the same, thereby causing the syrup to become 80 well mixed with the corn. 9c

The piston or plunger 40 of the pump is adapted to work through a stuffing-box 50, arranged on the upper end of the pump-cylinder.

The upper end of the piston 5 is preferably 95 conical, as shown, to facilitate the raising of the same through the corn in the hopper.

The operation is as follows: After the corn has been cut from the cobs it is fed into the hopper, and as the piston 5 is raised out of the cylinder 3 the corn in said hopper will run into the cylinder and chute. The piston will then be brought down by means of the reciprocating cross-head, as hereinbefore described, forcing its way through the corn in 100 the hopper until it reaches the upper end of the cylinder 3, at which time the cam 25 on shaft 12 will engage the block 24 on arm 22 and rock said arm, which will raise the valve 18 through the medium of the valve-rod 21 and permit the corn in the cylinder 3 and chute 4 to be forced out by the further 105 downward movement of piston. At the same time that the valve 18 is raised and the corn begins to discharge from the chute the pump-piston is being brought down in the pump by the crank-arm 45 on shaft 15, thereby 110 forcing the syrup contained therein through the pipe 48 into the valve-chamber 17, from whence it runs onto the discharging corn and mixes with the same. As soon as the cam 25 moves out from under the block 24 arm 22 will drop, thereby closing valve 18 and cutting off the discharge of corn. By this time 115 the crank-arm 11 and cross-head 8 will have moved the piston 5 to the limit of the downward movement. The crank 11 will then begin to force the cross-head and piston upwardly on the upstroke of the same, which movement will be auxiliated by the admission 120 of steam to the cylinder, as hereinbefore described. 125

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus fully described my invention, what I claim, and desire to secure by Letters Patent, is—

1. In a corn and syrup feeder for canning factories, the combination with a suitable frame, of a hopper, feed cylinder and chute, supported upon said frame, a valve arranged to close the discharge end of said chute, means for intermittently opening and closing said valve, a piston, arranged to operate in said cylinder to force the contents thereof out through said chute, means for reciprocating said piston, and means for feeding syrup to the contents of said hopper as they are discharged from said chute, substantially as described.

2. In a machine of the character described, the combination with a suitable frame, of a hopper, feed cylinder and chute supported upon said frame, a valve arranged to close the discharge end of said chute, means for intermittently opening and closing said valve, a piston arranged to operate in said cylinder to force the contents thereof out through said chute, means for reciprocating said piston, and a pump adapted to discharge syrup in predetermined quantities onto the contents of said hopper as they are being discharged from said chute, substantially as described.

3. In a machine of the character described, the combination with a suitable frame, of a hopper, feed cylinder and chute supported upon said frame, a valve arranged to close the discharge end of said chute, means for intermittently opening and closing said valve, a piston arranged to operate in said cylinder to force the contents thereof out through said chute, means for reciprocating said piston, means for periodically admitting steam to said piston as the same begins its upstroke whereby the movement of said piston will be auxiliated, a pump adapted to discharge syrup in predetermined quantities onto the contents of said hopper as they are being discharged from said chute and means for regu-

lating the quantity of syrup so discharged, substantially as described.

4. In a machine of the character described, the combination with a suitable frame, of a hopper, feed cylinder and chute, supported upon said frame, a valve arranged to close the discharge end of said chute, means for intermittently opening and closing said valve, a piston, arranged to operate in said cylinder to force the contents thereof out through said chute, a piston-rod fixed at its upper end to said piston, a cross-head connected to the lower end of said piston-rod, a driven shaft journaled in said frame, a crank-arm fixed to said shaft, a pitman-rod having one end connected to said cross-head and its opposite end having a slotted engagement with said crank-arm, a drive-shaft geared to said driven shaft to operate the same, a pump adapted to discharge syrup onto the contents of said hopper, as they pass through said chute, means for operating the piston of said pump and means for regulating the stroke of the same whereby more or less syrup may be discharged by the pump, substantially as described.

5. In a machine of the character described, the combination with a suitable frame, of a hopper, feed cylinder and chute supported by said frame, a sliding valve arranged to open and close the discharge end of said chute, a valve-stem fixed to said valve, an operating-rod connected at its upper end to said stem, an arm pivotally connected at one end to said frame and having its opposite end connected to said operating-rod, a block adjustably mounted on said arm, a driven shaft suitably journaled in said frame, a cam fixed to said shaft and adapted to engage said block and thereby open said valve, a piston arranged to operate in said feed-cylinder, means for operating said piston, and means for periodically supplying syrup in predetermined quantities to the contents of said feed cylinder and hopper as the same are being discharged through the feed-chute, substantially as described.

In testimony whereof I have hereunto set my hand in presence of two subscribing witnesses.

JOHN M. C. JONES.
